UNITED STATES PATENT OFFICE.

LOUIS S. FLATAU, OF ST. LOUIS, MISSOURI.

DISTILLING APPARATUS.

1,233,771.

Specification of Letters Patent. Patented July 17, 1917.

Application filed October 1, 1915. Serial No. 53,514.

To all whom it may concern:

Be it known that I, LOUIS S. FLATAU, a citizen of the United States of America, a resident of the city of St. Louis, State of Missouri, have invented certain new and useful Improvements in Distilling Apparatus, of which the following is a full, clear, and exact description, reference being had to the accompanying drawings, forming part 0 of this specification.

My invention relates to a distilling apparatus, particularly adapted for use in the distillation of crude oil, one of the objects being to produce an extremely simple and 5 highly efficient means for heating the substance to be distilled. With this object in view the invention preferably comprises a receptacle for the crude oil, a boiler including a water jacket surrounding said receptacle, a heating chamber arranged below said receptacle and water jacket, and a series 20 of flues extending through the water jacket, the flues being adapted to conduct the hot gases from the heating chamber so as to 25 heat the water around the oil receptacle. An apparatus so constructed is a very compact single structure constituting a retort and a heating plant combined with each other in such a manner that the heat is 30 transmitted most effectively from the heating chamber to the substance to be distilled.

The preferred form of the invention also includes means for conducting steam from the upper portion of the water jacket to the 35 lower portion of the oil receptacle, thus heating and agitating the crude oil. Owing to the peculiar manner in which the heating plant is associated with the oil receptacle, the water jacket serves as a boiler for producing 40 the steam which passes into the oil receptacle, at the same time forming part of the means for heating the exterior of said receptacle.

With the foregoing and other objects in 45 view the invention comprises the novel construction, combination and arrangement of parts hereinafter more specifically described and illustrated in the accompanying drawings wherein is shown the preferred embodiment of the invention; however, it is to be understood that the invention comprehends changes, variations and modifications which 50 come within the scope of the claims hereunto appended.

55 Figure I is a vertical section of an oil

still constructed in accordance with my invention.

Fig. II is a horizontal section.

Fig. III is an enlarged section of the gage 60 for indicating the oil level.

Fig. IV is a side elevation of the parts shown in Fig. III.

To illustrate the preferred form of the invention, I have shown an oil still comprising an oil receptacle A, a boiler in the form 65 of a water jacket B surrounding said oil receptacle, and a heating chamber C below said water jacket and oil receptacle. The heating chamber is provided with a grate 1 adapted for use in burning coal or similar 70 fuel, and a deflector 2 adapted for use in connection with an oil burner.

The oil receptacle is preferably a cylinder having a top wall 3 and a bottom wall 4, the latter forming part of the top wall of 75 the heating chamber.

The boiler or water jacket is an annular structure having an outer wall 5 associated with the side wall 6 of the oil receptacle to form an annular space around said oil 80 receptacle. The water jacket also includes an annular top wall 8 and an annular bottom wall 9, both of which are arranged between and secured to the walls 5 and 6. Flues 10 passing through the water jacket, 85 are secured at their ends to the walls 8 and 9. These flues are arranged around the oil receptacle A, as shown in Fig. II, and they serve as means for conducting hot gases from the heating chamber C, through the 90 water jacket, and then to a smoke hood 12 located above the oil receptacle and the water jacket and secured to the outer wall 5 of the water jacket. The oil receptacle A is preferably provided with a dome 13 95 which extends into the hood 12, the upper end of said dome being closed by a cover plate 14.

The annular wall 6 is provided with circular rows of radiating tubes 15 which extend into the oil in the oil receptacle A, each of said tubes being in communication with the boiler or water jacket B. The inner ends of tubes 15 are closed by caps 16 to prevent the fluid from escaping through 105 the tubes and into the oil receptacle. When the apparatus is in service, the tubes below the water level are filled with hot water, and the steam above the water level is free to flow into the upper rows of tubes. The 110

different radiating tubes 15 are thus heated by direct contact with the steam and hot water, and also by the heat transmitted from the annular wall 6 to which all of the tubes 5 are secured.

17 and 18 designate supply pipes for conducting crude oil to the receptacle A, and 19 and 20, respectively, designate valves for controlling the flow of oil through said supply pipes. Discharge pipes 21 and 22, leading from the bottom wall of the oil receptacle, are provided with valves 23 and 24. These valves are normally closed to prevent the escape of liquid from the bottom of the oil receptacle. An outlet pipe 25, secured to the upper end of the dome 13, is provided with branches 26 and 27 for conducting vapor from the oil receptacle for a purpose well understood in this art. Valves 28 and 29 may be opened and closed to regulate the flow of vapor through the pipes 26 and 27, respectively.

The means for conducting steam from the upper portion of the boiler or water jacket 25 B, preferably comprises a series of pipes 30 each of which extends from the upper portion of the annular wall 5 to a valve 31 near the lower end of said wall. Steam conducting pipes 32, extending across the angular boiler or water jacket B, are connected at their ends to the annular walls 5 and 6. 33 designates short pipe sections leading from valves 31 to the pipes 32, and 34 designates discharge pipes extending from the pipes 32, 35 into the lower portion of the oil receptacle, and terminating in down-turned discharge nozzles 35. The flow of steam into the lower portion of the oil receptacle may be regulated by operating the valves 31, located at 40 the exterior of the apparatus where they may be readily controlled by the operator.

After the oil has been introduced into the oil receptacle, the valves 19 and 20 are closed, and the valves 28 and 29 are opened to permit the gas, or vapor, to pass from the dome 13. The heat generated in the heating chamber is transmitted directly to the bottom wall of the oil receptacle, and the hot gases passing through the flues 10 serve as a most effective heating medium for the water in the boiler which surrounds the oil receptacle. The hot water and steam transmit heat to the annular wall 6 and also to the radiating tubes 15 which extend into the oil. 55 The many radiating tubes 15 are surrounded by the oil, so that the heating surface with which the oil is in direct contact, is very materially increased by applying said radiating tubes to the circular wall 5.

60 I also deem it a marked advantage to combine the boiler and heating chamber with the oil receptacle in the manner shown, for the reason that the boiler and oil receptacle derive their heat from a single heating chamber, and the heat of the boiler is transmitted

directly to the wall of the oil receptacle without the loss of energy which has heretofore been incurred in the transmitting of heat from one apparatus to another. Moreover, the combined heating chamber, boiler 70 and oil receptacle A, is a single apparatus, occupying a comparatively small space, and possessing a high degree of efficiency which cannot be obtained by the use of a number of separate and distinct structures located at 75 points remote from each other.

In addition to constituting a most effective means for transmitting heat to the surface of the oil receptacle, the boiler or water jacket B serves as means for generating steam 80 which flows through the pipes 30 to the valves 31, thereafter passing to the lower portion of the oil receptacle. The steam introduced in this manner, agitates the oil to create a circulation of oil along the heating 85 surfaces of the oil receptacle, at the same time liberating gas from the oil, and as the steam flows outwardly through the pipes 25, 26 and 27 it carries small gas bubbles which would not otherwise pass freely from the oil. 90

Upon the completion of the distilling operations, the valves 23 and 24 may be opened and steam may be introduced into the oil receptacle to force the asphaltum, paraffin, or other substances, from the bottom of the 95 oil receptacle and through the pipes 21 and 22.

The gage for indicating the level of the oil comprises a float 40 secured to a rocker arm 41, the latter being secured to a rock shaft 42 having a pointer 43 at its outer end, as shown in Figs. III and IV. The rock shaft 41 passes through a tube 44 having its ends secured to the walls 5 and 6, and also through a tube 45 extending inwardly from the inner end of said tube 44. The bearings for the rock shaft 42 consist of a plug 46 secured to the inner end of tube 45, and a plug 47 screwed into the outer end of tube 44. A spring seat 48, arranged in the tube 44 as 100 shown in Fig. III, is provided with openings 49. To prevent the escape of fluid through the tubes 44 and 45, a valve 50 formed on the rock shaft 42, is fitted to a valve seat on the inner end of the plug 47 and forced into 110 engagement with said seat by a spring 51. The fluid tending to escape through the tube 44 would also tend to force the valve 50 into engagement with its seat. A stuffing box 52, at the outer end of plug 47, also serves as 115 means for preventing the escape of fluid through the pipe 44. The pointer 43 moves along a dial 54 in response to movements of the float 40, thus indicating the level of the oil in the oil receptacle. 120

125 I claim:

A distilling apparatus comprising a cylindrical oil receptacle provided with a vapor dome, an annular boiler shell surrounding and secured to said cylindrical oil receptacle 130

to form an annular steam boiler which surrounds the contents of said oil receptacle, a heating chamber below all of said parts, a hood arranged over said annular boiler and inclosing said vapor dome, and an annular row of flues extending through said annular boiler and communicating with said hood and heating chamber, said flues being located between said annular boiler shell and the cylindrical oil receptacle to provide means 10 for conducting hot products of combustion from said heating chamber through the annular boiler and into said hood.

LOUIS S. FLATAU.
